Primary Examiner — Wendy L Arminio*(74) Attorney, Agent, or Firm* — David R. Conklin; Kirton McConkie(57) **CLAIM**

The ornamental design for a spoon cap, as shown and described.

DESCRIPTION

FIG. 1 is a top perspective view of a spoon cap showing the new design in an open orientation.

FIG. 2 is a left elevation view thereof.

FIG. 3 is a right elevation view thereof.

FIG. 4 is a front elevation view thereof.

FIG. 5 is a back elevation view thereof.

FIG. 6 is a top plan view thereof.

FIG. 7 is a bottom plan view thereof.

FIG. 8 is a top perspective view thereof showing the new design in a closed orientation.

FIG. 9 is a left elevation view thereof.

FIG. 10 is a right elevation view thereof.

FIG. 11 is a front elevation view thereof.

FIG. 12 is a back elevation view thereof.

FIG. 13 a top plan view thereof; and,

FIG. 14 is a bottom plan view thereof.

The broken lines depict portions of the spoon cap that form no part of the claimed design.

1 Claim, 14 Drawing Sheets# US D905,551 S
